UNITED STATES PATENT OFFICE.

GEORGE HAL HARRINGTON, OF SEATTLE, WASHINGTON.

DEVICE FOR BENDING PIPES AND RODS.

1,289,747.

Specification of Letters Patent. Patented Dec. 31, 1918.

Application filed May 27, 1918. Serial No. 236,696.

To all whom it may concern:

Be it known that I, GEORGE HAL HARRINGTON, a citizen of the United States, and resident of the city of Seattle, county of King, and State of Washington, have invented certain new and useful Improvements in Devices for Bending Pipes and Rods, of which the following is a clear and exact specification.

10 This invention relates to improvements in pipe and rod bending machines and the object of this improvement is to provide a relatively light and portable machine of this nature that is efficient in operation and that 15 may be adjusted to bend pipes or rods to any desired curvature.

A further object is to provide a machine of this nature having a triangular frame the two side members of which are pivoted at 20 the apex and provided at the end opposite the apex with means for adjusting the side members toward or away from each other, and to provide grooved rollers which may be rotatably mounted on the frame members 25 and through which a pipe or bar of metal may be passed when it is to be bent.

The invention consists in the novel construction, adaptation and combination of parts of a pipe bending machine as will be 30 more clearly hereinafter described and claimed.

In the accompanying drawings Figure 1 is a plan view of a bending machine constructed in accordance with this invention. Fig. 2 35 is a view in side elevation of the same, and Fig. 3 is a view in cross section substantially on a broken line 3—3 of Fig. 2, certain parts being shown in elevation.

In certain forms of structural work and 40 particularly in reinforced concrete construction it is often desired to bend reinforcing rods or pipes into circular shapes of comparatively large diameter. This work must necessarily be done at the location where the 45 pipes or rods are being used for the reason that rods of this nature bent to a large diameter cannot be conveniently handled in shipment.

The device herein disclosed is designed 50 especially for this class of work and is mounted on wheels so that it may be easily moved from one place to another.

Referring to the drawings, throughout

which like reference numerals designate like parts, the numerals 5, 6, 7 and 8 designate 55 four frame members respectively.

The members 5 and 6 may be spaced apart by blocks 10 and rigidly secured to each other by bolts 11 as shown in Fig. 2 and the members 7 and 8 may be secured together in 60 spaced apart relation in similar manner.

When thus constructed the members 5 and 6 will form one side of a triangular frame, while the members 7 and 8 will form the opposite side, the members 5 and 6 being pivotally secured to the members 7 and 8 at the apex of the frame by suitable hinges 12.

Extending upwardly through the frame members 5 and 6 are two vertical shafts 13 and 14 upon the top ends of which are fixedly mounted two grooved rollers 15 and 16 respectively.

The shafts 13 and 14 are provided between the frame members 5 and 6 with fixedly mounted gear wheels 17 and 18 of the same 75 pitch diameter that mesh with each other in such a manner that when one of the shafts 13 or 14 is rotated the other shaft will be rotated therewith at the same speed but in an opposite direction.

The shaft 13 is provided on its top end with a crank 20 by which it may be rotated.

Extending upwardly through the frame members 7 and 8 in a position substantially opposite the vertical shaft 14 is a pivot 21 85 upon which is mounted a grooved roller 22.

The grooved rollers 15, 16 and 22 are all located in the same plane so that when a pipe or rod 23 is inserted between such rollers as shown in Fig. 1 and passed therethrough by turning the crank 20 it will be bent on a predetermined radius.

The amount of curvature that is imparted to the pipe 23 will be governed by the relative distance between the roller 22 and the 95 roller 16, and this distance may be varied by increasing or decreasing the angle between the two sides of the triangular frame.

For the purpose of varying this angle the end of the frame opposite to the apex is 100 provided with a tension screw 24 that passes through an enlarged hole 25 in the frame member 7, thence through an enlarged hole 26 in the frame member 5 and is screwed through a fixed nut 27 on the inside of the 105 member 5 as more clearly shown in Fig. 3,

so that it may be turned by a crank 28 to move the outer ends of the frame members closer together.

5 The enlarged holes 25 and 26 are provided to prevent binding or bending of the screw 24 as the outer ends of the frame members are moved toward or away from each other.

10 When a pipe or rod is being bent by the rollers 15, 16 and 22 and the outer end of the frame is supported against spreading by the screw 24, it is obvious that there will be a force exerted tending to move the bottom frame members 6 and 8 toward each other. This force is offset by providing a 15 compression screw 30 that has an enlarged end 31 that is adapted to abut against the frame member 6 and that is provided with a nut 32 that may be screwed outwardly against a plate 33 on the frame member 8.

20 The rear end of the frame is also adapted to be braced and strengthened by a cross bar 34 that may be pivoted securely between the frame members 7 and 8 by a bolt 35 and it may project through the space or opening between the frame members 6 and 5 as more 25 clearly shown in Fig. 1.

The rear end of the frame is preferably provided with legs 36 and with handles 37, and the front end of the frame is preferably 30 mounted on wheels 38 on a transverse axle 40 so that the device may be wheeled around like an ordinary wheel-barrow.

35 The axle 40 may be pivoted by a bolt 41 to the frame members on one side and may be secured to the frame members on the opposite side by a bolt 42 that passes through an arcuate slot 43 in the axle, the center of curvature of the slot 42 being the center of 40 the hinge 12, so that the axle 40 will always be substantially at right angles to the medial plane of the frame regardless of the angle of divergence between the two sides.

45 When the device is to be used it may be adjusted to give the desired curvature, the rods or pipes that are to be bent may be inserted within the grooved rollers, and the crank 20 turned to rotate the rollers 15 and 16 and thereby feed the rods or pipes through the machine.

50 It has been found in practice and it is not necessary to drive the roller 22, hence such roller is mounted for rotation on one side of the frame while the two driven rollers 15 and 16 are mounted for rotation on the opposite side of the frame, thereby making it possible to adjust the distance between the rollers 15 and 16 and the roller 22 without disturbing the arrangement of the driving mechanism by which the pipe is feeding 55 mechanism by which the pipe is fed through the several rollers.

60 It is obvious that changes in the precise form and arrangement of the several parts

embodied in this device may be resorted to within the scope of the following claims.

What I claim is—

65 1. A bending machine of the class described comprising a triangularly shaped frame having two sides that are pivotally connected with each other at the apex, devices adjustably connecting the divergent ends of said sides, grooved rollers mounted on each of the sides of said frame and means for driving certain of said grooved rollers.

70 2. A bending machine of the class described comprising a triangularly shaped frame having two sides that are pivotally connected with each other at the apex, devices adjustably connecting the divergent ends of said frame, a pair of grooved rollers mounted on one part of said frame, means 75 for driving said pair of rollers, and a single grooved roller mounted on the other part of said frame in the same plane with said two first named rollers.

80 3. A portable bending machine of the class described comprising two divergent frame members that are pivotally connected at one end, means adjustably connecting the opposite ends of said frame members, two shafts extending upwardly through one of said frame members, gear wheels fixedly mounted on each of said shafts and adapted to mesh with each other whereby when one of said shafts is rotated in one direction the other of said shafts will be rotated in an 85 opposite direction, grooved rollers fixedly mounted on the top ends of said shafts, a single grooved roller mounted for rotation on the other frame member, wheels supporting one end of said frame members and handles provided on the opposite end thereof.

90 4. A portable bending machine for pipes and rods comprising two divergent frame members that are pivotally connected at one end each of said frame members being 95 formed of two pieces that are rigidly secured together one above the other in spaced apart relation, two shafts extending upwardly through one of said frame members, enmeshed gearwheels mounted on said shafts 100 and disposed between the two pieces of said frame member, grooved rollers fixedly secured on the top ends of said shafts, a single grooved roller rotatably mounted on the other frame member and adapted to be 105 adjusted with respect to said two first named rollers by moving said two frame members toward or away from each other and wheels supporting said frame for movement from 110 place to place.

115 Signed at Seattle, Washington, this 20th day of May, 1918.

HAL HARRINGTON.
